(57) **CLAIM**

I claim the ornamental design for a leg sleeve, as shown and described.

DESCRIPTION

FIG. 1 is a front view of a leg sleeve, showing my new design;

FIG. 2 is an enlarged front view of the claimed region of FIG. 1;

FIG. 3 is an enlarged perspective view of the region denoted on FIG. 2; and,

FIG. 4 is another enlarged perspective view of the region denoted on FIG. 2.

The broken lines are provided for environmental purposes only and form no part of the claimed design.
